GLUING MECHANISM

Charles Z. Monroe, Detroit, Mich., assignor to
The American Paper Bottle Company, Toledo,
Ohio, a corporation of Ohio

Original application June 13, 1940, Serial No.
340,358. Divided and this application August
13, 1941, Serial No. 406,705

3 Claims. (Cl. 91—49)

This invention relates to mechanisms for applying coatings of glue or other materials in liquid or plastic form to the surfaces of paper articles and relates particularly to a mechanism of this general type which is designed and intended for use in the application of glue to the surfaces of the bottom end flaps of tubular paper containers just prior to movement of such end flaps into container bottom sealing position.

In Patent No. 2,047,891, granted July 14, 1936, there is described and illustrated a paper container of tubular type, square in cross section and the ends of which are sealed. One end, i. e., that end which is to subsequently become the container lower end, is provided with four bottom flaps, two major bottom flaps and two minor bottom flaps and, in the actual bottom closing operations, one side of each of the major bottom flaps is coated with an adhesive substance, following which the two minor bottom flaps are folded into bottom closing position, one major bottom flap then folded down on the two minor bottom flaps, the glue coated surface of this major bottom flap making contact with both minor bottom flaps, the second major bottom flap being finally folded down over the first mentioned major flap and pressure then applied to consolidate the several flaps into one rigid integral bottom structure. The present invention relates particularly to a mechanism for conveniently applying to one surface of each of the major bottom flaps of a container of the type described a coating of glue or other adhesive and by means of which this operation may be performed with great rapidity and in a thoroughly efficient manner. One embodiment of the invention is illustrated in the accompanying drawing in which:

Figure 1 is an elevation of the gluing mechanism, showing portions of its supporting means;

Figure 2 is a section on line 2—2 of Figure 1;

Figure 3 is a section on line 3—3 of Figure 2; and

Figures 4 and 5 are, respectively, sections on lines 4—4 and 5—5 of Figure 1.

It will be appreciated that in the usual case the gluing mechanism is positioned to function as one element of a larger machine and the mechanism which has been selected for disclosure by way of example is of a type which may advantageously form part of a machine for automatically erecting and forming containers from container blanks, coating them interiorly and exteriorly with a leak-proofing substance, charging them with a commodity to be dispensed, such for

instance as milk, and finally closing and sealing the same. Portions of the side frames of such a machine are indicated at 10 and 11 of the drawings and the various operating parts of the gluing mechanism are supported from these side frame members upon bridging means which includes brackets 12 and 13 bolted to the side frame members, respectively, and a supporting bar 14 the ends of which are bolted to the brackets 12 and 13, respectively, by securing bolts indicated at 16.

For gluing simultaneously the two major bottom flaps of a container such as that shown in Patent No. 2,047,891, previously referred to, two spaced glue-applying rolls are utilized, these rolls being indicated at 17, 17 in the drawings. A container body is indicated at 18 and the oppositely extending major bottom flaps of the container are indicated at 18a and 18b respectively. The rolls 17 for applying adhesive to flaps 18a and 18b are identical, and likewise the means associated with each of these rolls for supplying the same with adhesive. Therefore, it will only be necessary to describe one glue-applying roll with its associated cooperating elements.

Both glue-applying rolls 17 are mounted upon a common shaft 19 which is extended laterally through one or the other of the frame members 10 or 11 and the outer end of which is operatively connected to means for rotating the same, preferably to an electric motor by means of which the rolls may be rotated at a constant desired angular velocity. Each glue-applying roll 17 works between side plates 20, disposed at right angles to the axis of the roll, which tightly engages the end surfaces of the roll, the roll and the side plates, together with inclined plate 21, hereafter designated a spreader plate, defining a substantially V-shaped trough for the reception and storage of a small body of a suitable adhesive, as indicated at A in Figure 2. As the roll 17 revolves in the direction of the arrow indicated at B in Figure 2, it will carry upon its surface, after passing under the spreader plate 21, a thin layer of adhesive and the thickness of this layer is controlled by the position of the lower edge of the spreader plate with respect to the cylindrical surface of the roll. The spreader plate is attached by means of a screw 22, in a block 23 which is 45 slideable in a recess formed in the supporting bar 14, the block being retained in this recess by means of the pin 24 which projects through a cylindrical aperture formed in the rear of the block. A spring 25 normally tends to urge the block upwardly into contact with a plate 26

mounted on bar 14 but the block and spreader plate may be moved downwardly by rotating pin 24, the enlarged and threaded upper end of which passes through a threaded aperture in the upper plate 26.

The lower shoulder of the threaded portion of pin 24 bears upon the upper surface of block 23 and, when the pin 24 is rotated in one direction the block and spreader plate will be moved downwardly against the action of the spring and, when rotated in the opposite direction, will be lifted by the spring so as to follow upwardly the movement of the annular shoulder at the lower end of the threaded portion of the pin. A cover plate 30 is provided to prevent contamination of the adhesive A.

In passing through the gluing means the container end flap 18a moves along a predetermined pathway indicated by the chain line C in Figure 2, the upper surface of this end flap being engaged by the glue covered surface of the glue roller directly above it and the undersurface of the same flap being engaged and supported by a pressure roll 31, the distance between the surfaces of the pressure roll and gluing roll being normally adjusted so as to be less than the thickness of the paper from which the end flap 18a is fabricated.

It will be perceived upon an inspection of Figures 1 and 2 that the pressure roll 31 is mounted upon a shaft 32 which is pivotally hung by depending arms 33 from a supporting bracket 34 so that the pressure roll is adjustable along an arc centered on the axis of swing of arms 33, which axis is indicated at 35 in Figures 4 and 5. Normally, however, the pressure roll is resiliently held in the position in which it is shown in Figure 2 by a spring 36 one end of which bears against the swinging bracket which includes arms 33 and the other end of which bears against an adjustable nut 37 threaded upon the lower end of a stud 38 the upper end of which stud is attached to a stationary frame part. However, the swinging pressure roll support is limited in its movement under the influence of spring 36 by an adjustable contact screw 40, having a head 41 and a lock nut 42, the inner end of bolt 40 normally engaging a flat surface formed on the frame part 13. Hence the normal position of the surface of the pressure roll with respect to the surface of the gluing roll may be very definitely fixed without, however, making it impossible for the pressure roll to back away from the gluing roll whenever a major bottom flap is passed between them. Predetermined pressure of the upper surface of each major bottom flap against the gluing roll is thus assured. As will be observed from an inspection of Figure 3 the side plates 20 are retained in position by spring pressed detents 44, so as to be readily removable, the springs 45 also serving to lightly urge the plates 20 against the ends of the gluing roll, to maintain tight contact between the plates and the gluing roll ends at all times.

In the operation of the device, container bottom flaps, the upper surfaces of which are to be glue coated, successively pass by each glue roll in the specified manner, the path of movement of one such flap being indicated by the chain line C.

The means for supporting the container bottom flap prior and subsequent to its contact with the gluing roll and supporting pressure roll 31 is not illustrated, forming no portion of the present invention, but it will be readily apparent that, during the time that the upper surface of a container bottom flap is in contact with the surface of the gluing roll 17 the undersurface of the flap will be firmly supported by the pressure roll 31.

10 The degree of pressure applied by roller 31 against the work may be regulated as desired and likewise the thickness of the film of adhesive upon the surface of the gluing roll may be regulated by precisely adjusting the position of the spreader plate 21. By adjusting the positions of the spreader plate and pressure roll with respect to each other the desired film thickness of adhesive may be obtained.

This application is a division of my copending application, Serial No. 340,358, filed June 13, 1940.

Having thus described the invention, what is claimed as new and desired to be secured by Letters Patent is:

1. In a glue applying mechanism in combination, a support, a roll mounted on the support for rotation about a fixed axis, a block provided with a spreader plate mounted for sliding movement toward and away from the periphery of the roll, resilient means urging the spreader plate away from the roll, a pressure roll shiftable with respect to said first-mentioned roll for maintaining a moving sheet to be coated against the surface of the first-mentioned roll, and manually operable means for advancing the spreader plate toward the first-mentioned roll against the action of said resilient means.

2. In an adhesive applying mechanism, in combination, a support, an adhesive applying roll mounted on the support for rotation about a fixed axis, a spreader plate supported for adjustment radially of said roll, end plates for maintaining, in association with said spreader plate, a body of adhesive against said roll, spring pressed detents for urging said end plates against the ends of the roll and detachably securing them in such position, and means shiftable with respect to said roll for maintaining a moving sheet to be coated against the surface of said roll.

3. In an adhesive applying mechanism, in combination, a support, an adhesive applying roll mounted on the support for rotation about a fixed axis, a spreader plate supported for adjustment radially of said roll, end plates for maintaining, in association with said spreader plate, a body of adhesive against said roll, spring pressed detents for urging said end plates against the ends of the roll and detachably securing them in such position, a pressure roll cooperating with the adhesive applying roll, and means for shiftably mounting said pressure roll with respect to said adhesive applying roll including a spring to urge the pressure roll against the adhesive applying roll and a limit contact member to limit the shifting movement of the pressure roll, to maintain a moving sheet to be coated with the adhesive against the adhesive applying roll.

CHARLES Z. MONROE.
